CLAIM

The ornamental design for a door handle, as shown and described.

DESCRIPTION

FIG. 1 is an isometric view of a door handle showing a first embodiment of the design.

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof.

FIG. 7 is a bottom plan view thereof.

FIG. 8 is an isometric view of a door handle showing a second embodiment of the design.

FIG. 9 is a front elevation view thereof.

FIG. 10 is a rear elevation view thereof.

FIG. 11 is a right side elevation view thereof.

FIG. 12 is a left side elevation view thereof.

FIG. 13 is a top plan view thereof.
FIG. 14 is a bottom plan view thereof.
FIG. 15 is an isometric view of a door handle showing a third embodiment of the design.

FIG. 16 is a front elevation view thereof.

FIG. 17 is a rear elevation view thereof.

FIG. 18 is a right side elevation view thereof.

FIG. 19 is a left side elevation view thereof.

FIG. 20 is a top plan view thereof.

FIG. 21 is a bottom plan view thereof.

FIG. 22 is an isometric view of a door handle showing a fourth embodiment of the design.

FIG. 23 is a front elevation view thereof.

FIG. 24 is a rear elevation view thereof.

FIG. 25 is a right side elevation view thereof.

FIG. 26 is a left side elevation view thereof.

FIG. 27 is a top plan view thereof; and,

FIG. 28 is a bottom plan view thereof.

The shading lines shown in the drawings represent the approximate three-dimensional contour of the claimed design and are not intended to indicate surface decoration. The broken lines shown in the drawings illustrate portions of the door handle that form no part of the claimed
